UNITED STATES PATENT OFFICE.

WILLIAM W. KNIGHT, OF OXFORD, MISSISSIPPI.

COMBINATION BABY'S BED, CRADLE, AND WARDROBE.

1,336,240.

Specification of Letters Patent.

Patented Apr. 6, 1920.

Application filed November 29, 1918. Serial No. 264,604.

To all whom it may concern:

Be it known that I, WILLIAM W. KNIGHT, a citizen of the United States, residing at Oxford, in the county of Lafayette and State of Mississippi, have invented new and useful Improvements in Combination Babies' Beds, Cradles, and Wardrobes, of which the following is a specification.

This invention comprehends generally improvements in that class of inventions known as beds and more particularly relates to a combination baby's bed, cradle and wardrobe.

The invention has for its principal aim and object to provide a device of the above mentioned character designed so as to provide a swinging cradle capable of being locked in a stationary position in the main frame or else removed to permit of the extending of parts of the main frame to provide a bed or play pit, the main frame being incidentally designed to form a wardrobe for accommodating the infant's clothes.

More particularly the present invention contemplates the provision of a device of the above mentioned character wherein the main frame is of novel construction and is particularly designed so as to effectively swingably support the cradle element which when removed permits of the extending of the auxiliary side ends of the main frame to provide a crib or play pit, the construction and arrangement of the auxiliary sides being such that they may be readily collapsed into a compact position when the cradle is in position so as to not interfere with the swinging of the cradle in the main frame.

The invention has for an additional object to provide a device of the above mentioned character wherein the cradle element is of novel construction being provided with reticulated end sections and a removable reticulated hood designed so that they may be readily disassembled and folded to lie within the body of the cradle element to occupy only a minimum amount of space when it is not desired to use the same.

It is a more specific object of this invention to provide a device of the above mentioned character wherein improved means is employed for removably and swingably supporting the cradle element in the main frame; and to also provide coöoperative

means on the cradle element and on the main frame for holding the cradle against swinging movement.

It is an additional object of this invention to provide a device of the above mentioned character which is simple in construction, thoroughly reliable and efficient in its purpose and inexpensive in manufacture.

Other objects will be in part obvious and in part hereinafter set forth.

The invention accordingly consists in the features of construction, the combination of elements and the arrangement of parts which will be amplified in the construction hereinafter described and the scope of the application of which will be indicated in the appended claims.

The invention is clearly illustrated in the accompanying drawings, in which:

Figure 1 is a perspective view of the device showing the cradle in position in the main frame.

Fig. 2 is a longitudinal sectional view thereof.

Fig. 3 is a cross section taken on line 3—3 of Fig. 2.

Fig. 4 is a cross section taken on line 4—4 of Fig. 2.

Fig. 5 is a perspective detail showing the cradle collapsed and detached.

Fig. 6 is a longitudinal sectional detail of the cradle when closed.

Fig. 7 is a transverse sectional detail of the cradle when closed.

Fig. 8 is a perspective detail of the device with the cradle removed showing the auxiliary sides of the frame extended.

Fig. 9 is a transverse sectional detail thereof.

Fig. 10 is a top plan view thereof.

Fig. 11 is a detailed sectional view showing the means for latching the cradle against swinging movement.

Similar characters of reference are employed in all of the above described views, to indicate corresponding parts.

Referring now, more particularly, to the accompanying drawings there is provided a main frame comprising relatively high end pieces generally designated by the numerals 1 and 2 the upper portions of which are provided with openings 3 while the lower portions 4 are solid and are joined by main side pieces 5 while both the side pieces and

the solid portions of the end pieces support a platform 6. To provide the wardrobe for accommodating the clothes of a baby the main side pieces 5 are provided with openings 6' in which are mounted drawers 7 adjusted by knobs 8. In order to brace the frame and support the drawers a cross bar 9 is connected between the main side pieces 5 while a guide 10 is connected to this cross bar and co-operates with the combined guides and drawer supports 11 on the inner faces of the solid portions 4 of the end pieces for insuring of an easy opening and closing of the drawers. Rollers 12 of a conventional construction are connected to the bottom of the frame for facilitating the movement of the same about the floor. Auxiliary end pieces 13 are now employed and are preferably pivoted by means of hinges 14 to the upper surface of the platform 6 near the respective ends thereof while auxiliary side pieces 15 are swingably connected by means of hinges 16 to the inner surfaces of the main side pieces 5 near the upper edges thereof. The auxiliary end pieces 13 are designed so that they may be folded against the platform while the auxiliary side pieces 15 may be folded upon the auxiliary end pieces so that they lie in a compact position beneath the plane of the upper edges of the main side pieces or else they may swing upwardly into an extended position to provide a crib or play pit. Eyes 17 are connected to the inner surfaces of the auxiliary side pieces 15 near the ends thereof and are removably engageable by hooks 18 swingably connected to the inner surfaces of the auxiliary end pieces 13 and designed for engagement with the hooks to lock the auxiliary side and end pieces in an extended position. By this construction it is apparent that a spring and mattress of conventional design are adapted to be arranged on the top of the auxiliary side and end pieces when the latter are collapsed or folded to provide a bed or else arranged upon the platform when the auxiliary side and end pieces are extended thus providing a crib or bed or play pit, as desired.

As intimated, an improved cradle has been employed and consists of a body 19 of a substantially rectangular configuration comprising a base 20, side walls 21 and end walls 22. Reticulated end sections generally designated by the numeral 23 are now employed and each consists of a rectangular open frame 24 covered with screen 25 and these end sections are swingably connected as by hinges 26 to the upper edges of the end walls 22 of the body. A brace bar 27 is now employed while hooks 28 are connected to the undersurfaces thereof near the respective ends and are designed for engagement with sockets 29 carried by the inner faces of the end sections 23 being designed to maintain the end sections extended. It is to be noted that the upper surface of the brace bar lies beneath the plane of the upper edges of the end sections. A hood generally designated by the numeral 30 is now employed and consists of a sectional top and sides. The sectional top is composed of open rectangular sections or frames 31 covered with pieces of screen 32 and are swingably connected together by hinges 33 while to the outer side edges of these sections 31 are hinged the open rectangular sides or frames 34 of the top. Like the sections 31 these sections 34 are covered with pieces of screen 35. In applying the hood the meeting edges of the middle sections are designed to rest on the brace bar 27 while the sides 34 are swingable downwardly to rest on the upper edges of the side walls 21 of the body and bear against vertical bracing strips 36 carried by the inner faces of the end sections 23. Handles 37 are connected to the lower edges of the sides 34 to facilitate swinging thereof. By the construction shown it is apparent that either side of the hood may be conveniently raised so that the baby may be placed within the body which, of course, is adapted to receive a spring and mattress of conventional design.

In order to swingably and removably mount the cradle on the frame, hangers 38 have their lower ends pivotally connected near the lower corners of the end walls 22 of the cradle by means of suitable pivots 39 while the upper ends are formed with openings 40 and communicating slots 41. Headed pivots 42 project from the inner faces of the upper portions of the main end pieces 1 and 2 of the frame and are opposed to each other. The openings 40 in the hangers are designed to be placed over the headed pivots 42 so that the slots 41 may engage the shanks of the pivots 42 and in this manner swingably support the cradle on the frame. When connected in the manner described the under surface of the cradle is arranged in close proximity to the upper edges of the main side pieces 5 while the ends of the cradle are slightly spaced from the upper portions of the main end pieces 1 and 2 by means of the openings 40 it is apparent that the hangers and consequently the cradle may be disengaged. With a view toward providing an improved means for locking the cradle against movement when mounted in the frame catches generally designated by the numeral 43 project from the end walls 22 of the cradle and each catch consists of a horizontally disposed base portion 43' formed medially of its upper surface with a vertical wing 44. Keeper bars 45 are swingably connected to the lower edges of the openings 3 in the end pieces 1 and 2 by means of hinges 46 and are designed to be swung

inwardly at times and incidentally provided medially of one of their faces with notches 47 for embracing the vertical wings 44 of the catches 43 in such a manner that the base portions 43' of the catches serve to support the keeper bars when swung inwardly. Of course, when it is desired to swing the cradle the keeper bars are swung upwardly so as to rest on the lower edges of the openings 3 and be out of the path of movement of the cradle.

It is apparent that when the cradle is locked the same may be used in the nature of a crib or bed while the hood serves as a protector for the baby within the crib by preventing flies, etc., from bothering the baby.

When it is not desired to use the cradle the hood may be lifted upwardly while the sections of the top may be folded together and also folded in close relation with respect to the side sections and placed within the body of the cradle. The brace bar 27 may also be removed from position by disengaging the hooks from the sockets and placed within the body whereupon the end sections 23 may be folded inwardly to engage the upper edges of the side walls of the body 19 of the cradle, it being understood, of course, that the hood when folded lies beneath the plane of the upper edges of the side walls 21. The hangers, of course, may be disengaged from the pivots 42 and swung into close relation with the sides of the end walls of the body. It will thus be seen that the cradle may be folded to occupy a minimum amount of space when it is not desired to use the same.

It is believed in view of the foregoing description that a further detailed description of the operation of the invention is entirely unnecessary. Likewise it is believed that the advantages of the invention will be readily apparent.

What is claimed as new is:

1. A device for the purpose indicated embodying a main frame having end pieces, a cradle swingingly supported in the frame by suspension from the said end pieces, catches projecting from the end of the cradle, and keeper bars hingedly attached to the end pieces and movable from normally vertical planes to horizontal planes for engagement with the catches to temporarily lock the cradle against swinging movement.

2. A device of the character described including a frame composed of relatively high end pieces the upper portions of which are formed with openings while the lower portions are solid, side pieces connecting the solid portions of the end pieces, and a platform supported by the side pieces and the end pieces, a cradle positioned between the upper portions of the end pieces and above the side pieces, hangers having their lower ends swingably connected to the lower end

of the cradle and their upper ends detachably and swingably connected to the upper portions of the end pieces, catches projecting from the ends of the cradle, keeper bars swingably connected to the lower edges of the openings in upper portions of the end pieces and formed with notches for removably engaging the catches to hold the cradle against movement, and auxiliary side and end pieces hinged to the platform and the main side pieces respectively and foldable to lie beneath the plane of the upper edges of the main side pieces when the cradle is in position but extensible upwardly when the cradle is removed to provide a play pit.

3. A device of the character described including a frame composed of relatively high end pieces the upper portions of which are formed with openings while the lower portions are solid, side pieces connecting the solid portions of the end pieces, and a platform supported by the side pieces and the end pieces, a cradle positioned between the upper portions of the end pieces and above the side pieces, hangers having their lower ends swingably connected to the lower end of the cradle and their upper ends detachably and swingably connected to the upper portions of the end pieces, catches projecting from the ends of the cradle, keeper bars swingably connected to the lower edges of the openings in upper portions of the end pieces and formed with notches for removably engaging the catches to hold the cradle against movement, auxiliary end pieces hinged to the platform near the respective ends thereof, auxiliary side pieces hinged to the inner surfaces of the main sides and in spaced relation to the platform, the auxiliary end pieces being foldable to engage the platform while the auxiliary side pieces are foldable to engage the auxiliary end pieces and lie in a plane beneath the upper edge of the main side pieces to permit the swinging of the cradle, the auxiliary end and side pieces being also foldable upwardly when the cradle is removed to provide a crib, and co-operative means on the adjacent ends of the auxiliary end and side pieces for latching the same in extended position.

4. A device of the character described including a main frame comprising end pieces connected by side pieces, a platform supported by the end and side pieces and positioned beneath the plane of the upper edges of the side pieces, auxiliary end pieces hinged to the platform near the respective ends thereof and foldable at times to engage the platform, auxiliary side pieces hinged to the inner faces of the main side pieces at points above the platform and swingable at times to engage the auxiliary end pieces and lie beneath the plane of the upper edges of the main side pieces, the

auxiliary side and end pieces being also extensible upwardly to provide a pit, and co-operative means on the adjacent ends of the auxiliary end and side pieces for fastening the same in a substantially rigid position when extended.

5. A device of the character described including a frame composed of relatively high end pieces, side pieces connected to the end 10 pieces, and a platform supported by the side and end pieces, a cradle detachably and swingably mounted between the upper portions of the end pieces and disposed above the upper edges of the side pieces, and auxiliary side and end pieces hinged to the platform and the main side pieces respectively and foldable to lie beneath the plane 15 of the upper edges of the main side pieces when the cradle is in position but extensible upwardly when the cradle is removed to provide a play pit.

6. A device of the character described including a frame composed of relatively high end pieces, side pieces connected to the end 25 pieces, and a platform supported by the side and end pieces, a cradle detachably and swingably mounted between the upper portions of the end pieces and disposed above the upper edges of the side pieces, auxiliary 30 end pieces hinged to the platform near the respective ends thereof, auxiliary side pieces hinged to the inner surfaces of the main sides and in spaced relation to the platform, the auxiliary end pieces being foldable to 35 engage the platform while the auxiliary side pieces are foldable to engage the auxiliary end pieces and lie in a plane beneath the upper edge of the main side pieces to permit the swinging of the cradle, the auxiliary 40 end and side pieces being also foldable upwardly when the cradle is removed to provide a crib, and co-operative means on the adjacent ends of the auxiliary end and side

pieces for latching the same in extended position.

45

7. A device of the character described including a frame composed of relatively high end pieces, side pieces connecting the end pieces near their lower ends, and a platform supported by the side and end pieces, headed 50 pivots carried by the inner faces of the upper portions of the end pieces, a cradle, hangers having their lower ends swingably connected to the lower end corners of the cradle and their upper ends provided with 55 openings for engagement over the headed pivots and also provided with slots communicating with the openings for swinging engagement with the pivots, co-operative means on the end pieces and on the cradle 60 for removably latching the cradle against movement, and auxiliary side and end pieces hinged to the platform and the main side pieces respectively and foldable to lie beneath the plane of the upper edges of the 65 main side pieces when the cradle is in position but extensible upwardly when the cradle is removed to provide a play pit.

8. A device of the kind indicated embodying a main frame having end pieces, a 70 cradle swingingly supported in the frame by suspension from the said end pieces, catch members carried at each end of the cradle and each catch consisting of a horizontally disposed base portion and a central 75 vertical wing upstanding therefrom, and keeper bars hinged to the end pieces and formed each with a medial notch for engagement with the vertical wings of the catches, the keeper bars being movable from 80 vertical to horizontal planes to engage the catches to temporarily secure the cradle against movement.

In testimony whereof I affix my signature.

WILLIAM W. KNIGHT.
